(57) **CLAIM**

The ornamental design for a cabinet, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a cabinet showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof; and,

FIG. 8 is a bottom, rear and right side perspective view thereof.

The portions of the cabinet which are illustrated by the broken lines in the drawings or inside the border thereof form no part of the claimed design.

1 Claim, 8 Drawing Sheets
(6 of 8 Drawing Sheet(s) Filed in Color)
